(57) **CLAIM**

The ornamental design for an optical network element panel, as shown and described.

DESCRIPTION

FIG. 1 is a front view of the optical network element panel; and,

FIG. 2 is an isometric view of the optical network element panel.

The rear, top, bottom, left and right sides of the optical network element are unornamented.

The broken lines are shown for illustrative purposes only and form no part of the claimed design.
